[57] CLAIM

The ornamental design for an indicator label for used automobiles, as shown and described.

DESCRIPTION

FIG. 1 is a front elevational view of an indicator label for used automobiles showing my new design;

FIG. 2 is a side elevational view thereof; and

FIG. 3 is a rear elevational view thereof.

The stippling shown along the top and bottom edges of FIG. 1 represents an adhesive used to affix the label to a window of a used automobile.

FIG. 3

FIG. 2
